UNITED STATES PATENT OFFICE.

LORENZ BERBERICH AND GEORGE BERBERICH, OF PITTSBURGH, PENNSYLVANIA.

BROOM.

Application filed February 27, 1923. Serial No. 621,569.

To all whom it may concern:

Be it known that we, LORENZ BERBERICH and GEORGE BERBERICH, citizens of the United States, and residents of Pittsburgh, 5 in the county of Allegheny and State of Pennsylvania, have invented a new and useful Improvement in Brooms, of which the following is a specification.

This invention relates to brooms, and 10 more particularly to the reinforcing of brooms by an elastic covering permanently sewed onto the broom.

The objects of the invention are to provide a protective covering for the upper 15 portion of the broom, permanently attached to the broom in such manner that the broom straws, or "corn", will be stiffened at their upper portion, rendered more resilient, and prevented from breaking in the normal use 20 of the broom. Other objects of the invention are to provide a covering which will protect that portion of the broom which is ordinarily struck against objects of furniture or the like, to prevent the spreading 25 apart of the free ends of the corn, to retain the individual straws that may break, and generally to strengthen the broom body, and prolong its life, while retaining and increasing its natural resiliency.

30 Other objects of the invention comprise the dividing of the fibers or straws of the broom into small compact groups, and the surrounding of the whole with a flexible cover adapted to maintain the individual straws and the groups of straws in substantially straight position, whereby to give addition resiliency and strength to the broom.

Other objects and advantages will be apparent to those familiar with the art of 40 making and using brooms from the following specification:

Referring to the drawings, Fig. 1 is an elevation of a broom showing the reinforcing and enveloping member sewed thereon; 45 Fig. 2 is a central section through the middle of the broom in its widest dimension showing how the corn is divided into groups by transverse stitching; and Fig. 3 is a central vertical section through the broom at 50 right angles to that of Fig. 2, showing the bending of the broom and the reinforcing effect of our construction, when the broom is in use.

It is a well known fact that the ordinary 55 corn broom, as commonly constructed tends to become flared out at the corners through

use, and to have the straws bent out of line at their free end. Also that the straws tend to break off in use below the lowest line of stitching. These broken straws either 60 hang to the broom in a useless condition, or else are entirely lost.

The desirability of placing some form of band about the broom in order to keep the corn properly together, and to hold the individual straws straight, has long been known, and a number of different devices have been devised for securing these results.

Our construction is applied to an ordinary broom having a handle 1 to which is 70 attached a broom body 2 by means of wiring 3, in the ordinary manner. As is well known the corn is attached to such a broom in a round form, then it is compressed in a vise, which spreads it out to the ordinary 75 broom shape, and then the corn is stitched through by machinery to hold it permanently in the flattened shape.

In constructing our device we surround the broom with an elastic cover 4, preferably of rubber, while the corn is in the original round form. This band may be molded or formed into annular form, or may be merely a flat strip wound around with its ends overlapping. When the vise 80 is applied to flatten the broom out, this stretches the rubber and leaves it under tension about the broom in the form shown in Fig. 1. The broom is then sewed tightly through and through by a number of rows 85 of stitching as illustrated. This sewing comprises outer cords 5, which extend around the broom, and intermediate cross threads 6, which pass around the outer cords and through the body of the broom. 90 These threads 6, together with the surrounding cords 5, divide the corn into what are in effect bunches, and together with the stretched elastic envelope, which is bound on securely by the stitching, greatly reinforce and strengthen the broom body.

The elastic envelope extends for a material distance below the lowest stitching, and forms in effect a resilient skirt 7 below the last row of stitching, adapted to compress the free ends of the corn and so to keep any of it from breaking off at the lower row of stitching.

We have found from actual trial that this elastic band around the broom, under tension, when sewed on by the stitching directly through the corn as illustrated, makes a

very strong compact broom, while at the same time permitting the corn to bend sufficiently throughout the entire length of the broom, and so retaining the desired 5 flexibility and springiness. The sewing of the band tightly to the corn adds greatly to the strength and efficiency of the combination. As shown in Fig. 3, the broom body bends as a whole and the band on the 10 convex side is actually stretched between the stitches.

The simplicity, economy of material, and ease of manufacture of this structure is apparent. The sewing is only that which 15 has to be applied to brooms anyhow, and therefore our elastic band can be applied with almost no additional expense other than that due to the cost of the rubber itself. This is not large, and the resulting 20 additional length of life and additional efficiency in the use of the broom is far greater than the comparatively small increase in cost due to the addition of this element.

There is nothing to get out of order, nothing 25 requiring any manipulation, adjustment, or modification whatever by the user, and the band will last as long as the broom. The cover being flexible, can not possibly injure any furniture against which it may 30 strike, while at the same time it prevents the breaking of straws due to such accidental contact.

We believe that we are the first to actually 35 build into a broom a flexible envelope permanently held under tension, adapted to compress the broom, hold it straight, and to reinforce every straw of it, while at the same time retaining all of its resiliency and flexibility throughout its length. The bead

8 at the lower edge of the band reinforces 40 and strengthens it, adds to the pleasing appearance, and gives a greater tension at that point. The upper bead 9 protects the other edge of the band but is chiefly for ornament.

It will be obvious that this construction 45 applies to brooms of any form, as for example, whisk brooms, toy brooms, etc., though it is chiefly valuable for ordinary floor brooms.

We claim:

1. A broom comprising an ordinary corn body, an elastic band under tension around the middle portion thereof and retained thereon by rows of stitching extending through the broom and said elastic band, the band having a skirt portion extending below the lowest row of stitching, and ending short of the free end of the broom body. 55

2. A broom comprising an ordinary corn body, a rubber band around the middle portion thereof and sewed thereon, the band having a skirt portion extending below the sewing, and a terminal reinforcing bead on said band. 60

3. The combination with a broom comprising an ordinary corn body, of an elastic band surrounding and compressing the intermediate portion of the broom body but not extending to the free end thereof, and stitching extending through the band and broom 70 body. 65

In testimony whereof, we hereunto sign our names.

LORENZ BERBERICH.
GEORGE BERBERICH.
